Primary Examiner — R. Johnson

(74) *Attorney, Agent, or Firm* — Shane V. Cortesi

(57) **CLAIM**

The ornamental design for an ergonomic guitar strap, as shown and described.

DESCRIPTION

FIG. 1 is a front perspective view of an ergonomic guitar strap in accordance with the present invention in its assembled state.

FIG. 2 is a rear perspective view of the ergonomic guitar strap of FIG. 1 in its assembled state.

FIG. 3 is a left elevation view of the ergonomic guitar strap of FIG. 1 in its assembled state.

FIG. 4 is a front elevation view of the ergonomic guitar strap of FIG. 1 in its assembled state.

FIG. 5 is a right elevation view of the ergonomic guitar strap of FIG. 1 in its assembled state.

FIG. 6 is a rear elevation view of the ergonomic guitar strap of FIG. 1 in its assembled state.

FIG. 7 is a top plan view of the ergonomic guitar strap of FIG. 1 in its assembled state.

FIG. 8 is a bottom plan view of the ergonomic guitar strap of FIG. 1 in its assembled state.

FIG. 9 is a front perspective view of the ergonomic guitar strap of FIG. 1 in its unassembled state.

FIG. 10 is a perspective view of the ergonomic guitar strap of FIG. 1 in its assembled state and in use holding a guitar; and,

FIG. 11 is a perspective view of the ergonomic guitar strap of FIG. 1 in its assembled state and in use holding a guitar. The broken lines shown in the Figures depict environmental subject matter only and are not part of the claimed design.
